UNITED STATES PATENT OFFICE

164,304

SUN SHIELD

Paul H. Houston, Fairmont, W. Va.

Application October 20, 1950, Serial No. 12,640

Term of patent 14 years

(Cl. D57—1)

To all whom it may concern:

Be it known that I, Paul H. Houston, a citizen of the United States, residing at Fairmont, in the county of Marion and State of West Virginia, have invented a new, original, and ornamental Design for a Sun Shield, of which the following is a specification, reference being had to the accompanying drawings, forming part thereof.

Figure 1 is a side elevational view of a sun shield, showing my new design in full lines, the showing in broken lines being for illustration purposes only.

Figure 2 is a top plan view thereof;

Figure 3 is a rear perspective view thereof; and

Figure 4 is a perspective view thereof from the under side.

I claim:

The ornamental design for a sun shield, as shown and described.

PAUL H. HOUSTON.
